EXHAUST STEAM INJECTOR

Emanuel Rawson, North Bergen, N. J., assignor
to The Superheater Company, New York,
N. Y.

Application March 17, 1933, Serial No. 661,334

17 Claims. (Cl. 103—265)

The present invention relates to exhaust steam injectors. More particularly the invention relates to exhaust steam injectors of the type adapted to be operated primarily by exhaust steam from an engine and to be operated wholly by live steam when exhaust steam from the engine is not available. Still more particularly the invention relates to exhaust steam injectors of the type particularly adapted to supply feed water to boilers of locomotives and having associated therewith automatic control systems for shifting the injector from live steam operation to exhaust steam operation and vice versa.

Operating experience with injectors of the above general character has demonstrated faults in operation of these injectors and the control systems therefor, among which is the tendency of the injectors to spill or "break", that is, to cease proper operation, when the injector shifts from live steam operation to exhaust steam operation, and with certain types of control systems to shift rapidly back and forth between live steam and exhaust steam operation under certain conditions of pressure of the exhaust steam available for operating the injector.

The general object of the present invention is to improve upon the control of exhaust steam injectors so as to eliminate the above-mentioned difficulties of operation and to provide an improved control system for exhaust steam injectors which will insure continuous injector operation when the injector is shifted from live steam to exhaust steam operation and which will prevent the fluttering or chattering action of the control system in rapidly shifting back and forth from one type of operation to the other, regardless of the pressure conditions of the exhaust steam available for injector operation.

The specific nature of the invention, together with the manner in which the general object and other and more detailed objects of the invention are attained, will appear more fully in the following description of a preferred form of apparatus for carrying the invention into effect, taken in conjunction with the accompanying drawings forming a part of this specification.

In the drawings Fig. 1 is a side elevation of part of a locomotive boiler showing the application thereto of an exhaust steam injector having a control system embodying the invention, and

Fig. 2 is a more or less diagrammatic sectional view on a large scale of a part of the injector and the control system shown in Fig. 1.

Referring now to Fig. 1, reference character 10

indicates the locomotive boiler and 12 is the exhaust steam injector for supplying feed water to the boiler. Water is supplied to the injector through feed pipe 14 and is delivered through the delivery pipe 16 to the boiler. One of the engine cylinders is designated at 18 and from the exhaust steam space of the cylinder casting exhaust steam is delivered to the injector through the exhaust steam supply pipe 20. Live steam for operating the injector and for operating the control system is supplied through the pipe 22 connected to the boiler turret and controlled by the manually operable main control valve 24 located in the cab of the locomotive. Control of the amount of water fed to the boiler by the injector is effected through the water regulating mechanism operated by the control handle 26 also located in the cab of the locomotive.

Turning now to Fig. 2 wherein the injector and control system are shown in detail, the injector is of known type comprising injector body 28 providing a low pressure steam chamber 30. Co-axially mounted in the injector body are the main low pressure steam nozzle 32, the water nozzle 34 and the secondary low pressure steam nozzle 36. Nozzles 32 and 36 are in communication with the steam chamber 30 and the water nozzle 34 is in communication with the water chamber 38 to which water is supplied through the feed pipe 14. Flow of water to chamber 38 is controlled by the steam pressure actuated valve 40 preferably seated by means of spring 42 and adapted to be opened by piston 44 to which steam is admitted through passage 46.

Flow of exhaust steam to chamber 30 is controlled by the exhaust valve 48 which in the present embodiment is of the double seated balanced type closed by spring 50 and opened by the steam actuated piston 52 to which steam is admitted through the passage 54.

Live steam at high pressure is supplied from pipe 22 by way of passage 56 in the injector to a high pressure steam nozzle 58, the discharge opening of which is located within the main low pressure steam nozzle 32. In the type of injector illustrated which is intended to deliver water against relatively high boiler pressures, a relatively small jet of high pressure live steam is employed at all times when the injector is in operation. This steam is supplied through nozzle 58 and is hereinafter termed "supplementary steam". The present invention, however, is not limited in its application to injectors of the type intended to deliver against

high pressures and is equally applicable to injectors delivering against relatively low pressures and in which the supplementary steam nozzle may be omitted.

5 Live steam at low pressure is admitted to chamber 30 when exhaust steam is not available through passage 60 and ports 62 around the supplementary steam nozzle 58. This live steam of low pressure will hereinafter be referred to as "auxiliary steam".

10 Flow of steam to passage 60 is controlled by a double faced valve 64 located in a valve housing indicated generally at 66. Valve 64 comprises a head located in chamber 68 and has a lower face seating to close the inlet of passage 60 and an upper face seating to close communication between chamber 68 and chamber 70, the latter forming a cylinder in which the piston-like portion 72 of valve 64 is slidably mounted. Chamber 68 is placed in communication with the live steam supply pipe through the small orifice or choke port 74 and valve 64 is urged toward this lower seat by means of spring 76.

15 Chamber 70 is placed in communication with the live steam supply from pipe 22 by way of passages 78 and 80 in the valve housing 66 and flow of live steam from passage 78 to passage 80 is controlled by a relay valve 82 having a double faced head in chamber 84. At its upper end chamber 84 is vented to atmosphere or other zone of low pressure through pipe 86 and, as will be observed from the drawings, when the head of the relay valve is on its lower seat, passage 80 and chamber 70 are vented to atmosphere and the supply of live steam from passage 78 is prevented from reaching chamber 84. The position of relay valve 82 is controlled by a piston portion 88 located in chamber 90, the upper face of the piston being exposed to pressure from steam in passage 78. Chamber 90 below the piston is also placed in communication with passage 78 by means of a small orifice or choke port 92. Chamber 90 is connected by means of pipe 94 to a pilot valve of the diaphragm actuated type contained in housing 96 and comprising a needle or pin valve 98 controlling communication between pipe 94 and vent pipe 100, the outlet end of which is preferably in communication with the low pressure steam chamber of the injector. Valve 98 is preferably arranged to be opened by spring 102 and to be closed by pressure of steam admitted to chamber 104 in the housing 96 below the diaphragm 106.

20 Passage 54 leading to the exhaust valve operating piston is connected by means of pipe 108 to the passage 80 connecting chambers 70 and 84. An automatically operated vent valve, the housing of which is indicated generally at 110, is connected by means of pipe 112 to the exhaust steam supply pipe 20 at a place in the latter adjacent to the exhaust valve 48 and preferably, as shown in Fig. 2, at the lowest point in the exhaust steam supply pipe 20. This valve 25 comprises a movable valve member 114 having a piston part 116 slidably mounted in the valve casing and having a lower valve face 118 adapted to engage a seat 120 in the housing to close communication between chamber 122 with which pipe 112 communicates and an atmospheric vent opening 124. The valve member is urged toward open position by means of spring 126 acting on the lower face of the valve piston and chamber 128 is connected to the pipe 108 by the branch pipe 130. The lift of the valve member 114

from its seat, under the influence of spring 126, is preferably made adjustable and in the embodiment illustrated this adjustment is effected by means of the adjustable plug 132 in the cover of the valve housing which provides an abutment limiting the upward movement of the valve member 114. Chamber 122 extends laterally of the casing as at 134 and a pipe 136 connects the chamber portion 134 with the chamber 104 in which is located the diaphragm 106.

25 The major portion of the injector and control apparatus above described is known and functions in known manner as hereinafter briefly described.

30 Let it be assumed that exhaust steam is not available and the injector is started by opening the main control valve 24. Live steam at high pressure flows through pipe 22 and passage 46 to act on the water valve piston to admit water to the injector. It also flows to the supplementary steam nozzle 58. With no exhaust steam available in the supply pipe 20 it is apparent that there will be no pressure in pipe 136 and consequently spring 102 of the diaphragm valve will act to keep this valve open. With the diaphragm valve open, chamber 90 below the relay valve piston is vented to a zone of low pressure through pipes 94 and 100 and high pressure steam admitted through passage 78 to the upper face of the relay valve piston causes the relay valve to seat against its lower seat, thus venting chamber 84 to atmosphere. This in turn vents pipe 108 to atmosphere and permits the exhaust valve to remain closed under the influence of the exhaust valve spring 50. Chamber 70 above the double seated valve 64, which may be termed the automatic or change-over valve of the system, is also vented to atmosphere and high pressure live steam entering chamber 68 through the port 74 causes the change-over valve to seat against its upper seat, thus placing the auxiliary steam passage 60 in communication with chamber 68. Steam flows to the low pressure chamber of the injector through passage 60 and ports 62 and is reduced in pressure by virtue of the throttling action of the choke port 74. The injector, under the assumed conditions, is thus supplied with water, high pressure supplementary live steam and low pressure auxiliary live steam and operates under these conditions as a live steam injector.

35 Under the assumed conditions it is to be noted that pipe 130 leading from the automatic vent valve is vented to atmosphere by way of pipe 108 and the automatic vent valve, under the influence of spring 126, is open to vent the exhaust steam supply pipe adjacent to the injector to the atmosphere.

40 If, with the injector operating as a live steam injector in above described manner, exhaust steam becomes available for operating the injector the action of the control system in shifting the injector is as follows:

45 The presence of exhaust steam in pipe 20 causes pressure to be built up in chamber 134 (in a manner to be described more in detail later) and this pressure is transmitted to the diaphragm valve to cut off communication between pipes 94 and 100. Steam is trapped in pipe 94 and pressure is built up under the relay valve piston 88 causing the relay valve to be shifted to its upper position in which the vent 86 is closed and passages 78 and 80 are placed in communication. High pressure steam thus flows to the chamber above the change-over valve and

moves this valve to its lower seat, shutting off communication between chambers 68 and the auxiliary steam passage 60. Simultaneously, high pressure steam flows through pipe 108 to the exhaust valve piston to open the exhaust valve and to thereby permit exhaust steam to flow from the supply pipe 20 to the low pressure steam chamber of the injector in place of the auxiliary live steam, the supply of which has been cut off by the shifting of the change-over valve. Also, high pressure steam flows through pipe 130 and acts on the piston of the automatic vent valve to force the latter down and seat it to close the atmospheric vent 124.

The present invention is concerned chiefly with the automatic vent valve apparatus associated with the exhaust steam supply pipe and the manner in which this and the diaphragm valve chamber are connected into the system.

As previously mentioned, when exhaust steam injectors are shifted from live steam operation to exhaust steam operation by means of an automatically operating control system, it frequently happens that operation of the injector is interrupted and the injector must be restarted by manual manipulation of the main control valve.

The reason for this failure at times of injectors to properly shift from live steam operation to exhaust steam operation has in the past not been understood although numerous different theories have been advanced, which theories have from time to time been proved to be erroneous since the remedies indicated by such theories have failed to solve the problem of eliminating this interruption of injector operation. I have discovered that the cause of interruption in injector operation when the shift from live steam operation to exhaust steam operation takes place, and in the case of injectors operating under normal conditions and with properly adjusted parts, is due to the entry and trapping of air or other non-condensable gases in the exhaust steam supply pipe during the periods when the latter is not filled with exhaust steam. Air may enter this pipe through the exhaust passages of the engine and combustion gases from the smoke box of the boiler may be drawn into this box when the locomotive is drifting with the throttle closed, since under these conditions the tendency is for the engine cylinders to draw gases into the exhaust passages of the engine and the condensation of steam in the supply pipe 20 tends to draw air and gases from the engine passages into this pipe. When the engine throttle is opened after a period of engine idleness, and exhaust steam flows into the supply pipe 20, it will be evident that the steam entering the pipe will tend to trap the air in this pipe and force it into the injector when the control system is operated to effect opening of the exhaust valve of the injector. Inasmuch as injectors of the character under discussion are usually installed at the rearward end of the locomotive adjacent to the cab and the exhaust steam is supplied from the cylinder passages at the forward end of the locomotive, the exhaust steam pipe 20 must be of considerable length and consequently a considerable quantity of air may be entrapped therein. It is this quantity of entrapped air which causes the break in injector operation since under the conditions as above outlined a considerable quantity of non-condensable air and/or gas is forced into the steam chamber of the injector

before the exhaust steam enters the injector. The lack of condensable low pressure steam in the injector after the auxiliary live steam supply is cut off due to shifting of the change-over valve causes the injector to cease to operate properly and the jet formed by the condensation of steam is destroyed.

In accordance with one phase of the present invention this difficulty is overcome by the provision of the automatic vent valve which vents the exhaust pipe to atmosphere when the injector is operating as a live steam injector and there is opportunity for air or other non-condensable gases to collect in the exhaust steam supply pipe.

In order to illustrate how the automatic vent valve eliminates the difficulty heretofore encountered, let us consider the sequence of events which occur with the injector operating as a live steam injector and when exhaust steam becomes available. With the injector operating as a live steam injector the automatic vent valve is open as is also the diaphragm valve. When exhaust steam flows into the supply pipe 20, air which is trapped in this pipe is free to flow to the atmosphere through the automatic vent or drain valve, and this valve will obviously remain open until high pressure steam is supplied to it through the pipe 130. Steam will not be supplied through this pipe until the relay valve is shifted from the position it occupies when the injector is operating on live steam. Let it be assumed that the exhaust steam flow has established a pressure in the diaphragm chamber sufficient to close the pilot valve, thus closing the vent passage from the chamber below the relay valve piston.

In the arrangement illustrated it will be noted that the pipe 94 has a considerable volume and an appreciable length of time will elapse after closure of the pilot valve before flow of steam through the restriction 92 will cause the pressure below the relay valve to rise sufficiently to cause this valve to shift its position. In other words, pipe 94 may be employed to provide a timing chamber which will act to delay the shifting of the relay valve with respect to the closing of the pilot valve by a period of, for example, from 15 to 20 seconds. During whatever delay period is provided, the automatic vent valve is still open and the exhaust valve controlling flow to the injector is still closed. Thus, ample time may be provided to insure the clearing of all air and other non-condensable gases from the exhaust pipe before the exhaust valve is opened. It will be evident that from the standpoint of clearing the exhaust pipe of air and other non-condensable gases, the period of delay in individual instances may vary considerably and in many instances this delay may not be necessary to effect change-over of operation of the injector without spilling, as the flow of exhaust steam to the injector may force substantially all of the air out of the exhaust pipe by the time the pilot valve or other primary actuating valve of the control system is actuated.

When the exhaust valve is opened to admit exhaust steam to the injector, the automatic vent valve is closed to prevent continued flow of exhaust steam from the supply pipe 20. Conversely, at the time when the exhaust valve is closed, the automatic vent valve is opened. In the illustrative embodiment the automatic vent valve is fluid pressure actuated and the action of this

valve in relation to the action of the exhaust valve is obtained by connecting these valves to a common source of operating steam. It will be evident, however, from the nature of the 5 interaction of the two valves that mechanical connection between the valves may be readily employed to cause one valve to be opened when the other is closed and vice versa.

By connecting the vent valve in the manner indicated, this valve also acts to drain 10 from the exhaust pipe any condensate which may have collected in this pipe, thus insuring against the admission to the steam chamber of the injector of a quantity of water 15 which would have to pass through the low pressure steam nozzle or nozzles of the injector.

Considering now the matter of the shifting back and forth or chattering of the control 20 system under certain exhaust steam pressure conditions, the manner in which the present invention overcomes this difficulty may best be understood by first considering the action which 25 takes place in the forms of apparatus as heretofore employed.

When exhaust steam is employed as the actuating medium for controlling the shifting of 30 the injector, chattering may occur due to fluctuations in the pressure of the exhaust steam when the engine is first started or is operating at very low speeds. In the past numerous attempts have been made to provide some kind of 35 pressure equalizing arrangement whereby these pressure fluctuations may be ironed out and a relatively steady pressure applied to the pilot valve. Experience, however, has demonstrated 40 that the expedients of this nature heretofore resorted to are unsatisfactory in service and the difficulty has been largely overcome in the past by the provision of timing means between the pilot valve and the change-over valve acting to 45 delay shift of the latter until a predetermined period after actuation of the pilot valve. This arrangement permits momentary closing of the pilot valve under the impulse of exhaust steam puffs before the exhaust steam pressure becomes steady, without causing the injector to be shifted to exhaust steam operation.

In accordance with one of the aspects of the 50 present invention, the difficulty heretofore encountered in preventing chattering due to the above cause is eliminated without having to resort to timing means in the control system, because of the action of the automatic vent valve 55 means in providing a source of comparatively steady exhaust steam pressure even under conditions of pulsating pressure in the exhaust steam supply pipe.

By reference to Figure 2 it will be evident that 60 due to the comparatively small cross-sectional area of the passage 138 as compared with the cross-sectional area of the chamber 134 and the outlet 140 from this chamber when the automatic vent valve is open, steam flowing to chamber 134 will tend to provide a relatively stable 65 pressure in this chamber even when it is supplied thereto in puffs. When the engine is first started and puffs of steam are delivered through passage 138, the pressure in chamber 134 will remain at too low a value to cause actuation 70 of the pilot valve which is connected to this chamber by means of the pipe 136 and by suitably relating the cross-sectional areas of the inlet and outlet openings of this chamber, the pressure in the chamber may be maintained below 75 that required to shift the control system

until steam is supplied through the inlet 138 at a rate which can be effected only by the existence in the exhaust steam pipe of a relatively steady pressure of exhaust steam at a pressure suitable for proper injector operation.

An important practical consideration in connection with this arrangement is that pressure equalization in chamber 134 may be obtained without having to resort to a small throttling orifice at the inlet 138, since the fact that the 10 automatic vent valve closes immediately upon shift of the injector to exhaust steam operation renders unobjectionable a comparatively high rate of flow through chamber 134 to the atmosphere. The practical importance of this lies in 15 the fact that, as experience has proven, a small orifice employed for pressure equalizing or other purposes will soon become clogged and inoperative because of impurities such as carbonized lubricating oil and other foreign matter carried 20 into the exhaust pipe by the exhaust steam from the engine.

Another cause of chattering of the control 25 system is caused under certain conditions by pressure drop in the exhaust pipe when the exhaust valve is opened and steam admitted to the injector, and the action which takes place in apparatuses heretofore employed is substantially as follows:

Under average operating conditions experience 30 has shown that an exhaust steam pressure actuated diaphragm pilot valve of the type which has been found best suited for this work acts to shift the injector to exhaust steam operation when the exhaust steam pressure reaches a value of approximately one and one-half pounds per square inch and acts to shift the injector back to live steam operation when the exhaust steam pressure falls to a value of approximately one and one-quarter pounds per square inch. In other words, there is a differential of about one-quarter pound per square 35 inch in the pressures which cause actuation of the diaphragm valve to shift injector operation. 40

It is this relatively small differential pressure 45 of one-quarter of a pound which is the cause of much of the trouble heretofore encountered with chattering, and experience has demonstrated that because of the numerous related functions of the control system it is highly impracticable 50 to alter the present type of valve so as to alter the value of this differential pressure without incurring other difficulties in the operation of the control system.

For purposes of illustration let it be assumed 55 that the injector is operating as a live steam injector and that the engine is running and producing exhaust steam at a pressure of less than one and one-half pounds. Further, let it be assumed that the engine is operating at sufficiently 60 high speed so that the exhaust pressure is substantially uniform, that is, not pulsating. If now the engine throttle is opened slightly, increasing the exhaust steam pressure to one and one-half pounds per square inch, the injector changes to 65 exhaust steam operation since this pressure is one of the critical pressures for the diaphragm valve. As the exhaust valve of the injector opens, exhaust steam is drawn into the injector and condensed and the flow of exhaust steam in 70 the pipe 20 results in a pressure drop in this pipe which is reflected in the pressure existing in the diaphragm chamber. If this pressure drop exceeds one-quarter of a pound, causing the exhaust pressure acting on the diaphragm to drop 75

below the critical pressure of one and one-quarter pounds, the control system acts to shift the injector back to live steam operation. When this shift occurs and the exhaust valve is closed, the 5 pressure in the exhaust pipe again builds up to one pound and a half (assuming that in the meantime there has been no change in the position of the main engine throttle) and the injector again shifts back to exhaust steam operation. 10 This shift again causes pressure drop in the exhaust steam supply pipe due to the opening of the exhaust valve in the injector and the shift to live steam operation again results. As long as the exhaust steam pressure conditions in the 15 supply pipe 20 remain in the critical range, the injector is likely to continue to shift back and forth between live steam operation and exhaust steam operation, and experience has proved that locomotive engines are frequently operated in the 20 range which produces exhaust steam at pressures within the critical range. The shifting of the injector back and forth from one type of operation to the other does not necessarily cause the injector to cease to operate properly, even when 25 the automatic vent valve is not employed, since this rapid shifting of operation or fluttering takes place when exhaust steam is continuously available in the exhaust steam supply pipe. The continued change-over of operation does, however, 30 result in premature wear of the parts of the control system, particularly the valves which have been found in practice not only to be subject to premature wear but also to be subject to premature breakage due to crystallization under 35 the continued hammering action of rapid shifting of position and engagement with valve seats under the influence of high steam pressures.

The action of apparatus according to the present invention to eliminate this undesirable operation is as follows:

It will be recalled that in the connection between the exhaust steam supply pipe 20 and the automatic vent valve there is provided a chamber 134 from which steam is conducted to the 40 operating chamber of the diaphragm valve. It will be evident that the area of the passage 138 leading to this chamber and the passage 140 connecting this chamber with the atmosphere may be related so that a predetermined pressure drop may be obtained between chamber 134 and the exhaust pipe 20 when the vent valve is open 45 and steam is flowing through the vent valve under the influence of a given pressure head in the exhaust steam supply pipe 20. Let us assume that the areas of the passages 138 and 140 are fixed to produce a pressure drop of one-half pound per square inch between chamber 134 and the exhaust pipe when the vent valve is open and the pressure in the exhaust 50 pipe is within the range of from one and one-half to two pounds per square inch. Now, let us assume that the engine is working so as to produce an exhaust steam pressure of one pound per square inch. Under this condition the injector will work as a live steam injector. With live steam operation the injector exhaust 55 valve is closed, the vent valve is open and exhaust steam is blowing through the vent valve to atmosphere. Pressure in the exhaust pipe is one pound per square inch but in the chamber 134 and consequently in pipe 136 and the diaphragm chamber it will be approximately one-half pound per square inch less, that is, approximately one-half pound per square inch. Now 60 let us assume that the engine throttle is open

to a degree raising the pressure in the exhaust steam pipe 20 to one and one-half pounds per square inch. This will result in a pressure in the chamber 134 of only one pound per square inch and the injector would continue to operate on live steam. When the pressure in the exhaust steam pipe reaches two pounds per square inch, a pressure of one and one-half pounds per square inch is reached in chamber 134 and since this pressure corresponds to one of the critical pressures of the diaphragm valve, the change-over to exhaust steam operation takes place. As soon as the exhaust valve of the injector opens and the automatic vent valve closes, pressure of exhaust steam in the pipe 20 drops from two 10 pounds to, let us say, one and one-half pounds, due to the flow of steam into the injector, but since the vent valve closes substantially simultaneously with the opening of the exhaust steam valve, flow of steam through chamber 134 has 15 ceased and the pressure in this chamber is instantly equalized with the one and one-half pound pressure which exists in the exhaust steam supply pipe under the conditions assumed. Pressure in the pipe 136, therefore, remains at 20 one and one-half pounds after the change to exhaust steam operation occurs and since this pressure is higher than the one and one-quarter pound diaphragm pressure which is critical with respect to change-over of operation from 25 exhaust steam to live steam, the injector remains on exhaust steam operation and rapid shifting and chattering of the control system is prevented.

Recalling that the injector is now operating on exhaust steam with a pressure of one and one-half pounds in the supply pipe 20, chamber 134 and pipe 136, let it be assumed that the engine throttle is closed until the steam pressure in these elements drops to one and one-quarter pounds. This causes the injector to shift back to live steam operation. The exhaust valve closes and the vent valve opens. Since we have assumed that opening of the injector exhaust valve with one and one-half to two pounds pressure in the supply pipe 20 results in a pressure drop of one-half pound in this pipe, it will be evident that closing of the exhaust valve as the injector comes back to live steam operation will result in a rise in pressure in the exhaust steam pipe of about one-half pound. This causes the pressure in this pipe to rise from the assumed one and one-quarter pounds to approximately one and three-quarters pounds. However, when this building up of pressure in pipe 20 occurs due to closing of the exhaust valve, the vent valve is open and a one-half pound pressure drop is established between pipe 20 and chamber 134. Thus we have a one and three-quarter pound pressure in pipe 20 and a one and one-quarter pound pressure in chamber 134 and pipe 136. As this one and one-quarter pound pressure is less than the one and one-half pound pressure required to shift the injector to exhaust steam operation, the injector remains on live steam operation and again no rapid shifting or chattering of the control system occurs. In other words, the vent valve automatically compensates for the pressure drop in the exhaust pipe which occurs when the exhaust valve of the injector is open and prevents chattering of the control system.

In the case of the example just described, the apparatus provides for change-over to exhaust steam operation at two pounds pressure and a 75

change-over to live steam pressure at one and one-quarter pounds pressure. In other words, a differential pressure of three-quarter pounds is provided. The same control system without the vent valve arrangement will produce a differential pressure of only one-quarter pound which will result in chattering of the system.

It will be evident that by varying the areas of steam flow to and from the chamber 134, with respect to each other, the amount of pressure drop between the exhaust pipe and this chamber may be varied and consequently the differential between the pressures required to shift the injector to exhaust steam operation and to live steam operation may also be varied. In the embodiment illustrated, the amount of pressure drop provided is conveniently adjusted by means of the adjustable plug 132 which limits the lift of the vent valve from its seat and consequently controls the free flow area of the passage 140 connecting the chamber 134 with the atmosphere.

While for purposes of illustration and for explaining the nature of the invention and the manner in which the apparatus embodying the invention operates, a specific form of exhaust steam injector and a specific form of control system involving the use of a relay valve and an exhaust steam pressure actuated pilot valve of the diaphragm type have been shown, it will be evident that the invention is not limited in its application either to this specific form of injector or to this specific form of control system and may equally well be applied to other forms of injectors and control systems in which different specific arrangements of parts are employed to obtain injection with low pressure steam and to obtain the desired shifting of the injector from one type of operation to the other.

It will also be evident that the construction and arrangement of the automatic vent or drain valve may be varied within the scope of the invention and that certain features of the invention may be employed to the exclusion of others. For example, the features of the prevention of chattering of the control system under different exhaust steam pressure conditions may be obtained through the employment of apparatus, the sole function of which is with respect to this feature and which does not function as an apparatus for venting the exhaust pipe of air.

Also, it will be evident that the vent valve feature may be applied to injectors shifted by control systems operating in response to the presence or absence of high pressure steam in the line supplying the main engine cylinders. If applied to such systems, it is desirable to provide a timing feature in order that the exhaust valve may remain closed for a predetermined period after live steam is admitted to the engine, so as to insure the lapse of sufficient time before the vent valve closes to permit all of the trapped air to be vented from the exhaust steam conduit. This timing may conveniently be provided by an arrangement such as that comprising the pipe 94 in the present embodiment or an expansion chamber arrangement such as that of chamber 134 may be employed with the expansion chamber connected to the live steam supply line.

What I claim is:

1. Apparatus of the character described, comprising an exhaust steam injector of the type adapted to be operated by exhaust steam from

an engine and to be operated by live steam when exhaust steam is not available, conduits for supplying live steam and exhaust steam to the injector, vent valve for venting the portion of the exhaust steam conduit adjacent to the injector to prevent flow of air and non-condensable gases to the injector through the exhaust steam conduit and means for causing said valve to close upon shifting of the injector from live steam operation to exhaust steam operation.

2. Apparatus of the character described, comprising an exhaust steam injector of the type adapted to be operated by exhaust steam from an engine and to be operated by live steam when exhaust steam is not available, conduits for supplying live steam and exhaust steam to the injector, and an automatic control system for shifting the injector from live steam operation to exhaust steam operation and vice versa, said system comprising a valve for controlling flow of exhaust steam from the exhaust steam conduit to the injector, a valve for venting the portion of the exhaust steam conduit adjacent to the injector, and means for automatically closing the second mentioned valve when the first mentioned valve is opened and for opening the second mentioned valve when the first mentioned valve is closed.

3. Apparatus of the character described, comprising an exhaust steam injector of the type adapted to be operated by exhaust steam from an engine and to be operated by live steam when exhaust steam is not available, conduits for supplying live steam and exhaust steam to the injector, and a fluid pressure actuated control system for shifting the injector from live steam operation to exhaust steam operation and vice versa comprising a fluid pressure responsive valve for controlling the flow of exhaust steam from the exhaust steam conduit to the injector and a fluid pressure responsive valve for venting the portion of the exhaust steam conduit adjacent to the injector, and means for substantially simultaneously admitting pressure fluid to said valves to cause the first mentioned valve to open and the second mentioned valve to close when the control system is actuated to shift the injector from live steam operation to exhaust steam operation.

4. Apparatus of the character described, comprising an exhaust steam injector of the type adapted to be operated by exhaust steam from an engine and to be operated by live steam when exhaust steam is not available, conduits for supplying live steam and exhaust steam to the injector, and a control system for automatically shifting the injector from live steam operation to exhaust steam operation and vice versa, the said system comprising a valve for controlling flow of exhaust steam from the exhaust steam conduit to the injector, a valve for venting a portion of the exhaust steam conduit adjacent to the injector, the second mentioned valve being arranged to be closed when the first mentioned valve is opened and to be opened when the first mentioned valve is closed, a pilot valve for controlling actuation of the control system, said pilot valve acting in response to a rise in exhaust steam pressure to a predetermined value to cause the control system to shift operation of the injector from live steam operation to exhaust steam operation, and timing means for delaying opening of the first mentioned valve and closing of the second mentioned valve for an appreciable period after actuation of the pilot valve due to

rise in exhaust steam pressure to the predetermined value.

5. Apparatus of the character described, comprising an exhaust steam injector of the type 5 adapted to be operated by exhaust steam from an engine and to be operated by live steam when exhaust steam is not available, conduits for supplying live steam and exhaust steam to the injector, a fluid pressure actuated control system 10 for automatically shifting the injector from live steam operation to exhaust steam operation and vice versa, said control system comprising a fluid pressure responsive valve for controlling flow of exhaust steam from the exhaust steam 15 conduit to the injector, a fluid pressure responsive valve for venting the portion of the exhaust steam conduit adjacent to the injector, the first mentioned valve being adapted to be opened by admission of pressure fluid thereto and the 20 second mentioned valve being adapted to be closed by the admission of pressure fluid thereto, a pilot valve responsive to rise in pressure of the exhaust steam to a predetermined value for causing said system to shift operation of the 25 injector from live steam to exhaust steam, fluid pressure actuated means controlled by actuation of said pilot valve for admitting pressure fluid substantially simultaneously to the two first mentioned valves, and timing means for delaying 30 actuation of said fluid pressure actuated means for an appreciable period after actuation of said pilot valve due to rise of exhaust steam pressure to said predetermined value.

6. Apparatus of the character described, comprising an exhaust steam injector of the type 35 adapted to be operated by exhaust steam from an engine and to be operated by live steam when exhaust steam is not available, an exhaust steam supply conduit connecting the engine and the 40 injector, a control system for shifting the injector from live steam operation to exhaust steam operation and vice versa, a combined vent and drain passage leading from the lowest portion of said conduit adjacent to the injector, a valve 45 controlling flow through said passage, and means operating in response to actuation of the control system to shift the injector to exhaust steam operation for closing said valve.

7. In apparatus of the character described, a 50 conduit for supplying exhaust steam from an engine to an injector, a valve for controlling flow of steam from said conduit to the injector, a valve for venting the portion of the conduit adjacent to the injector to a zone of lower 55 pressure, and means for causing substantially simultaneous shifting of said valves to open and close, said means being arranged to cause one of said valves to open when the other of the valves closes and vice versa.

- 60 8. Apparatus of the character described, comprising an exhaust steam injector of the type 60 adapted to be operated by exhaust steam from an engine and to be operated by live steam when exhaust steam is not available, a conduit for supplying exhaust steam from the engine to the injector, an automatic control system including 65 pressure responsive actuating means for shifting operation of the injector from live steam operation to exhaust steam operation and vice versa, 70 means providing a passage leading from said conduit to a zone of lower pressure, said passage being formed so that a predetermined pressure difference is obtained between a portion of said passage and said conduit when exhaust steam 75 is flowing through the passage, a connection for

conducting actuating fluid from said portion of said passage to said pressure responsive means, a valve for controlling flow of steam through said passage, and means for closing said valve in response to actuation of said pressure responsive means to cause the control system to shift the injector from live steam operation to exhaust steam operation.

9. Apparatus of the character described, comprising an exhaust steam injector of the type 10 adapted to be operated by exhaust steam from an engine and to be operated by live steam when exhaust steam is not available, a conduit for supplying exhaust steam from the engine to the injector, an automatic control system 15 including pressure responsive actuating means for shifting operation of the injector from live steam operation to exhaust steam operation and vice versa, means providing a chamber in communication with said conduit, said chamber 20 having an outlet communicating with a zone of low pressure and the areas of the inlet to and the outlet from said chamber being related so that a predetermined difference in pressure is obtained between the pressure in said chamber 25 and the pressure in said conduit when exhaust steam is flowing through said outlet, a connection for conducting actuating fluid from said chamber to said pressure responsive means, a valve for controlling flow of steam through said 30 outlet, and means for closing said valve in response to actuation of said pressure responsive means to cause the control system to shift the injector from live steam operation to exhaust 35 steam operation.

10. Apparatus of the character described, comprising an exhaust steam injector of the type adapted to be operated by exhaust steam from an engine and to be operated by live steam when exhaust steam is not available, a conduit 40 for supplying exhaust steam from the engine to the injector, an automatic control system including pressure responsive actuating means for shifting operation of the injector from live steam operation to exhaust steam operation and vice versa, means providing a chamber in communication with said conduit, said chamber having an outlet communicating with a zone of low 45 pressure and the areas of the inlet to and the outlet from said chamber being related so that a predetermined difference in pressure is obtained between the pressure in said chamber and the pressure in said conduit when exhaust steam is flowing through said outlet, a connection for conducting actuating fluid from said chamber to said pressure responsive means, a valve for controlling flow of steam through said outlet, the position of said valve when fully open determining the area of the outlet from said chamber, 50 adjustable means for varying the lift of the valve from its seat when in fully open position, and means for closing said valve in response to actuation of said pressure responsive means to cause the control system to shift the injector from live steam operation to exhaust steam 55 operation.

11. Apparatus of the character described, comprising an exhaust steam injector of the type adapted to be operated by exhaust steam from an engine and to be operated by live steam when exhaust steam is not available, a conduit for supplying exhaust steam from the engine to the injector, an automatic control system including pressure responsive actuating means for shifting 70 operation of the injector from live steam operation to exhaust steam operation and vice versa, 75 means providing a passage leading from said conduit to a zone of lower pressure, said passage being formed so that a predetermined pressure difference is obtained between a portion of said passage and said conduit when exhaust steam is flowing through the passage, a connection for

- tion to exhaust steam operation and vice versa, an automatic vent valve, means for placing said valve in communication with said conduit at a place adjacent to the injector comprising a connection providing a chamber having an inlet in communication with said conduit and an outlet controlled by said valve, the area of said outlet being related to the area of said inlet so that the pressure in said chamber when the valve is open and exhaust steam is being vented from said conduit through said valve is less by predetermined amount than the pressure in said conduit, a connection for conducting actuating fluid from said chamber to said pressure responsive means, and means for closing said valve in response to actuation of said pressure responsive means to cause the control system to shift the injector from live steam operation to exhaust steam operation.
12. Apparatus of the character described, comprising an exhaust steam injector of the type adapted to be operated by exhaust steam from an engine and to be operated by live steam when exhaust steam is not available, a conduit for supplying exhaust steam from the engine to the injector and an automatic control system including actuating means responsive to exhaust steam pressure for shifting operation of the injector from live steam operation to exhaust steam operation and vice versa, means providing a passage leading from said conduit to a zone of lower pressure and having an inlet relatively restricted with respect to the outlet, a conduit providing communication between said passage and said actuating means, and a valve for automatically closing said outlet when the control system is actuated to shift the injector to exhaust steam operation.
13. In a control system for exhaust steam injectors, means operative when exhaust steam is available but not supplied to the injector for creating a pressure differential, means operative in response to the lower of the pressures of said pressure differential for causing admission of exhaust steam to the injector when the lower of said pressures rises to a predetermined value, and means for equalizing said pressure differential when the exhaust steam is supplied to the injector, the second mentioned means being responsive to said equalized pressure and operating to cause the supply of exhaust steam to the injector to be shut off when said equalized pressure falls to a second predetermined value.
14. In a control system for an exhaust steam injector, means operative when exhaust steam is available but not supplied to the injector for creating a pressure differential due to flow of exhaust steam, a pressure responsive actuating device responsive to rise of the lower of the pressures of said pressure differential to a predetermined value to cause admission of exhaust steam to the injector, and means for stopping said flow of exhaust steam to equalize said pressure differential when exhaust steam is admitted to the injector, said pressure responsive actuating device being responsive to said equalized
- pressure and operating to cause supply of exhaust steam to the injector to be shut off when said equalized pressure falls to a second predetermined value.
15. In a control system for an exhaust steam injector adapted to receive steam from the exhaust steam conduit of an engine, pressure responsive actuating means for governing the admission of exhaust steam to the injector, means for venting to a zone of relatively low pressure a portion of the exhaust steam supplied through said exhaust steam conduit, means for causing expansion of the vented steam to a lower pressure in its path of flow to said zone whereby to reduce the value of pressure variations of the steam, and means placing said pressure responsive actuating means in communication with the portion of said path of flow wherein the steam is expanded to said lower pressure.
16. In a control system for an exhaust steam injector adapted to receive steam from the exhaust steam conduit of an engine, pressure responsive actuating means for governing admission of exhaust steam to the injector, means for venting to atmosphere a portion of the exhaust steam supplied through said exhaust steam conduit, means for causing expansion of the vented steam to a lower pressure in its path of flow to atmosphere whereby to reduce the value of the pressure variations of the steam, means placing said pressure responsive actuating means in communication with the portion of said path of flow wherein the steam is expanded to lower pressure, said pressure responsive actuating means operating to cause admission of exhaust steam to the injector when the pressure in said portion of the path of flow of the vented steam rises to a predetermined value, and means for automatically shutting off the flow of steam to atmosphere when exhaust steam is admitted to the injector.
17. In a control system for an exhaust steam injector, means including automatic valve means for controlling the admission of auxiliary live steam and exhaust steam to the injector in alternation, means operative when exhaust steam is available but not supplied to the injector for creating a pressure differential due to flow of exhaust steam, pressure responsive actuating means operative in response to rise of the lower of the pressures of said pressure differential to a predetermined value for causing actuation of said automatic valve means to effect admission of exhaust steam to the injector, means for equalizing said pressure differential when exhaust steam is supplied to the injector, said pressure responsive actuating means being responsive to said equalized pressure and causing actuation of said automatic valve means to shut off the supply of exhaust steam to the injector when said equalized pressure falls to a second predetermined value, and means for delaying the actuation of said automatic valve means by said pressure responsive actuating means to effect admission of exhaust steam to the injector.

EMANUEL RAWSON.
